UNITED STATES PATENT OFFICE.

HARRY C. HOCHSTADTER, OF PHILADELPHIA, PENNSYLVANIA.

HOLDER FOR DENTAL FLOSS AND OTHER THREAD.

Application filed February 18, 1922. Serial No. 537,446.

To all whom it may concern:

Be it known that I, HARRY C. HOCHSTADTER, a citizen of the United States, residing in the city and county of Philadelphia, 5 State of Pennsylvania, have invented new and useful Holders for Dental Floss and Other Thread, of which the following is a specification.

My invention consists of a device for holding dental floss, silk or other thread, the same embodying means for holding the thread tightly on the stock of the device.

The invention is satisfactorily illustrated in the accompanying drawing, but the important instrumentalities thereof may be varied, and so it is to be understood that the invention is not limited to the specific details shown and described, as long as they are within the spirit or scope of the claims.

20 Figure 1 represents a perspective view of a device for holding dental floss or other thread embodying my invention.

Figure 2 represents a central longitudinal section thereof.

25 Figure 3 represents a side elevation thereof.

Figure 4 represents a transverse section on line 4—4 Figure 3, on an enlarged scale.

Similar numerals of reference indicate 30 corresponding parts in the figures.

Referring to the drawings.

1 designates a tubular stock, and 2 designates a tubular body on the forward end of which latter is the head 3 which is connected 35 with the rear end of said stock, said body being adapted to contain floss, or silk thread 4 as the holder therefor which may be wound on a spool or quill 5 in said body, said body being also adapted to form the handle of 40 the device. In the present instance, the stock is of conical form and the body of cylindrical form.

In the wall of said body is an opening 6 and in the adjacent portion of the wall of 45 said stock is the opening 7 whereby the silk may be drawn from the holder through said openings into said stock and so brought to the discharge end 8 of the stock 1.

9 designates a swinging arm which over- 50 hangs the exterior of the stock and has its rear end pivotally connected with the rear portion of the stock by the axis 10, said portion having therein the recess 11 which permits motions of said arm on said axis 55 to and from the stock.

Connected with said arm at its axis is the

cam 12 which enters the rear end of the stock forming an elbow with said arm and contacts with the end of the floss, silk, thread and forces the same against the bore of the 60 stock and thus tightly holds said end.

Connected with the arm 9 at its axis is the finger piece 13 which overhangs the exterior of the body 2 and forms a lever for operating said arm to and from the stock 65 and moving the cam 12 to and from the end of the thread in order to hold the latter or release it as the case may be.

In the forward end of the arm 9 is the eye 14 which is so located in relation to the 70 discharge end of the stock 1 as to receive the length of thread that is passed from the stock to the arm and form the bridge 15 of thread which will be employed to be inserted between teeth and cleanse the same which is 75 the object of the thread.

In the end of the arm 9 adjacent to the recess 11 is the eye 16 through which the thread is passed and from whence it enters said recess and consequently the bore of the 80 stock.

It will be seen that when the thread is run from the holder and passed through the stock, it leaves the discharge end of the latter and is directed to the arm 9 and reeved 85 through the eye 14 from which it is extended rearward along said arm, and its end is directed through the eye 16 into the recess 11 and from thence into the bore of the stock 90 when it is passed under the cam 12, the arm being properly manipulated by outward movement of the finger piece 13 to permit such disposition of the thread. Then the finger piece is moved towards the body 2 when the end of the thread contiguous to 95 the cam is clamped by the latter against the bore of the stock and is there interlocked and the thread is stretched and tightened and thus the bridge 15 is rendered taut for efficient service on the teeth. After the 100 thread is disposed in operative form on the device, it will be noticed that the thread has a bite in the openings 6 and 7 and so cannot be run off from the holder and as the end of the thread in the stock is clamped by the cam the thread is prevented from shifting and so the bridge preserves its position and tautness.

When a fresh bridge is desired the finger piece 13 is moved outwardly from the body 2, thus releasing the thread in such manner that the thread run from the body is loosened when it may be removed and cut 110

off, and a fresh length of the thread may be drawn out from the holder and disposed of as in the previous case resulting in a fresh bridge as is evident.

5. Having thus described my invention what I claim as new and desire to secure by Letters Patent, is:—

1. In a holder for thread of the character stated, a tubular stock, a guiding arm, an axis therefor, a handle lever extended from the axial end of said arm, a cam on said axial end, and an abutment in the bore of said stock for the thread which is engaged by said cam.

15. 2. In a holder for thread of the character stated, a tubular stock, a guiding arm, an axis therefor, a handle lever extended from the axial end of said arm, a cam on said axial end, an abutment in the bore of said stock for the thread which is engaged by said cam, and a container for thread carried by said stock.

3. In a holder for thread of the character stated, a tubular stock, a guiding arm, an axis therefor, a handle lever extended from the axial end of said arm, a cam on said axial end, an abutment in the bore of said stock for the thread which is engaged by

said cam, and a container for thread carried by said stock, said cam being rigid with said lever adjacent said axis.

4. In a holder for thread of the character stated, a container for thread, a tubular stock connected therewith in which the thread may be directed, a swinging arm on said stock, said arm having an eye which is adjacent to the discharge end of said stock, a lever-like member for operating said arm, and a cam-like member on said member within said stock adapted to engage the end of the thread and interlock the same.

5. In a holder for thread, a thread holder, a guide on said holder for the passage of the thread, a swinging device for distending the thread and forming a bridge of the thread in the length thereof, and a cam-like locking member in said guide adapted to engage the free end of the thread therein, said guide having in its wall a recess through which the thread may be directed to said locking member.

HARRY C. HOCHSTADTER.
